(57) **CLAIM**

The ornamental design for a bow light for a marine vessel as shown and described.

DESCRIPTION

FIG. 1 is a starboard side perspective view looking down at a bow light for a marine vessel according to our design.

FIG. 2 is a port side perspective view looking down.

FIG. 3 is top view thereof.

FIG. 4 is a front view thereof.

FIG. 5 is a starboard side view thereof; and,

FIG. 6 is a port side view thereof.

The broken lines in the figures show portions of the bow light and marine vessel which form no part of the claimed design.
